RADIANT GAS STOVE WITH TRANSPARENT AIR CHIMNEY

De Witt H. Wyatt, Nashville, Tenn.

Application September 18, 1946, Serial No. 697,686

8 Claims. (Cl. 126—92)

1

The present invention relates to heaters for use with either natural or artificial gas, of a kind which are usually portable and which may be positioned at any point in a room convenient to a gas connection. In some instances, these heaters may be placed in a recess in the wall of a room, such as in the conventional fire place recess.

A principal object of the invention is to provide gas heaters of the above general type which combine heating efficiency, cheapness of construction, and ornamental beauty to a marked degree.

A further object of the invention is to provide heaters of the above type which supply heat to a room by direct and indirect heat radiation in combination with circulating convection currents of hot air. In this connection, it is an important object of the invention to provide for vertical circulation of pure heated air through the front of the heater, this circulation being separate or isolated from that of the combustion gases, and at the same time to direct radiant heat from visible radiants in the heater in order to provide an attractive soft-light appearance.

Ancillary to the above, it is an object of the invention to provide a heater wherein the hot burned gases may be baffled through a hood of the heater at the front thereof, and wherein a most effective radiator action is supplied at the front of the hood by a plurality of angular metal radiator surfaces which trap the burned gases for a short period of time and change their directions radically in order to extract the maximum of heat units from the gases prior to their discharge at the back of the hood.

A further object of the invention is to provide a heater having transparent or glass front members which control the upward flow of both heated air and the heated or burning gases, and wherein the radiants, which may be of attractive design in their effect upon the fire, will be visible to the occupants of a room through the front of the heater.

It is also an object of the invention to provide such a heater composed of a minimum number of parts which may be cheaply fabricated and capable of convenient assembly with a minimum of labor.

Various other objects and advantages of the invention will become apparent as the description herein progresses.

2

In the drawings, which are illustrative of several preferred forms of the invention:

Figure 1 is a side elevational view of a simple heater design.

5 Figure 2 is a half front elevational view of the heater of Figure 1.

Figure 3 is a top plan view of the portion of the heater depicted in Figure 2.

Figure 3a is a detail sectional view of the andiron connection, taken along the line 3a—3a of Figure 3.

10 Figure 4 is a partial front sectional view of the body of the heater, showing the position and relation of the gas burner.

Figure 4 is a transverse vertical sectional view of the heater, taken along the line 5—5 of Figure 4, this heater being of a design which does not employ the separate front andiron supports as in Figures 1—3.

15 Figure 6 is a top plan view of the heater of Figures 4 and 5.

Figure 7 is an enlarged detail horizontal sectional view through one end of the heater, showing the arrangement for attaching the structural parts of the base to one another, omitting the glass chimney for simplicity. In this view, a portion of the trim plate 40 is broken away to clarify the section in Figure 7a.

20 Figure 7a is a vertical sectional view taken along the line 7a—7a of Figure 7.

Figure 8 is a transverse vertical sectional view of a further modification of the invention, wherein a vented radiator hood is employed, said hood being shown in section along the line 8—8 of Figure 9.

25 Figure 9 is a front view of the radiator hood of Figure 8.

Figure 10 is a partial vertical sectional view of the radiator hood, taken along the line 10—10 of Figure 9.

30 Figure 11 is an enlarged front view of the radiator hood of Figure 8.

Figure 12 is a top plan view of the radiator hood of Figure 8, partly in section.

35 Figure 13 is a back view of the combustion gas outlet from the back of the hood.

Figure 13a is an end view of the hood shown in Figure 9.

40 Figure 14 is a transverse vertical sectional view of a further modification of the invention, wherein glass covers are employed immediately in front of the radiants.

Figure 15 is a half front elevational and half longitudinal sectional view of the heater of Figure 14.

Figure 16 is a top half plan view of the heater of Figure 14 with the hood omitted in the right half of the view.

Figure 17 is an enlarged partial horizontal sectional view of the aforesaid heater, showing details of the separate glass shields or covers for the radiants, the view showing the top edges of the glass shields.

Referring to Figures 1, 5, and 6, the base of the heater comprises a rear member 10 and a front member 12, said members being cast or otherwise formed of a light metal such as aluminum. The rear member has integral therewith opposite end legs 14, and the front member likewise has integral therewith opposite legs 16, or in the case of the andiron embodiment shown in Figures 1, 2 and 3, the front legs are omitted in favor of the andiron legs to be described.

The rear and front base members 10 and 12 are hollow as shown in Figure 5, providing an open space between them, and they are secured together at each end by respective vertically extending flange portions 20 and 22 (Figure 7), said flanges being gripped together by clamping plate C which embraces said flanges, said clamping plate having an aperture centrally therethrough to receive a bolt 25 which is secured by a nut 26 as shown in Figure 7.

In order to provide an enclosure for a burner tube 30 (best shown in Figure 5) a bent guard plate 32 is provided extending between the ends of the front base member 12, this plate having rearwardly bent portions 34 (Figure 7a) at each of its ends (Figure 7) terminating in outwardly extending vertical lugs 36 with bolt holes therethrough and through which the bolts previously mentioned may pass, said bolts having heads 38 which bear against the inner face of the end portions 34. The lugs 36 lie between the flange portions 20 and 22, and the clamping plates C have similar lugs 39 which lie between said flange portions.

With this construction, when the nut 26 is tightened, the clamping plate C serves to press the flange portions 20 and 22 together and thus hold the base sections in rigid relation with respect to one another. The securing assembly just described may, if desired, be covered by ornamental dressing plates 40 through which the bolts 25 likewise extend, there being a nut 42 on the extreme outer end of each bolt to clamp the dressing plates in position to cover the union between the front and rear base sections. As shown in Figures 2 and 4, this ornamental dressing 40 may extend for a considerable distance upwardly along the ends of the heater to enhance its finished effect, and may engage over an abutment on the hood as shown to retain the hood and back in proper position on the base.

Resting on the top edges of the base members just described, and on the top edge of the guard plate 32, is a horizontal plate 48 which provides a support for the refractory back B of the heater, and for a plurality of radiants R which are disposed in side by side relation along an indented open channel-way 52 formed around a central longitudinal opening along the length of the supporting plate 48. A conventional burner tube 50 equipped with the usual outlet gas nozzles 56 is supported by bolts 51 adjacent the ends of the supporting plate 48 to depend therefrom with a number of the nozzles or jets 56 positioned be-

neath each of the radiants. The back B of the heater has a forwardly extending top 62 which provides a gas space 64 above the radiants, and this top is beveled on its rear edge as shown to support a hood 65 likewise of refractory material, said hood having a downwardly depending lip 66 which covers the tops of the radiants when viewed from the front. The top 62 of the back B terminates short of the ends of the back, and at each end of the back there are integral forwardly extending end walls 67. The hood 65 has downwardly inclined end covering portions 68 which rest on the top surfaces 69 of the end walls 67, as shown in Figure 4. In order to secure the hood in place, there is a tie rod 70 which extends throughout the length of the burner, this tie rod passing through apertures in the upper ends of the finishing strip 40, and through the portions 68 of the hood, the ends of the tie rod being secured by nuts as shown, thus holding the parts firmly together while securing the end dressing plates 40 as shown.

Referring to Figures 3 and 5, it will be noted that the front base member 12 has a wall 72 of somewhat rectangular configuration, leaving an open space 74 for the upward passage of air in front of the radiants. The wall 72 is inwardly flanged near its top as at 76, and on this flange a curved heat resistant glass front 78, formed to the same configuration as the opening 74, is supported, said glass front extending rearwardly as at 80 to form a complete enclosure in front of the radiants. Referring to Figure 4, the front outer edges of the end sections 67 of the back are channeled vertically as at 81 to receive the rearward edges of the glass chimney to thus form a completely closed chimney effect.

It will be evident from the above that the base member and the back B, together with the glass front, constitute a casing open at its top and bottom and having front and rear walls and opposite end walls.

It will be understood that any appropriate means may be provided to vent the gases from the hood, as by means of any form of discharge connection leading from the hood chamber 64, if venting of gases is desired, although this may not be regarded as essential in simple designs. Appropriate means may be provided to seal the hood 65 to the edges of the back B to prevent discharge of burned gases into the room if this is regarded as undesirable. In this connection, it will be noted that the forward lip 66 of the hood extends downwardly to a point above the upper ends of the radiants in order to direct the hot gases into the hood.

With the arrangement just described, and referring particularly to Figures 1 and 5, it will be understood that the usual gas connection will be made with the burner tube 30, as at 82 in Figure 1, and the burner 30 will present mixed gas and air at the burner tips 56 (Figure 5). Additional or secondary air is permitted to pass upwardly as at 84 beneath the burner guard plate 32 and this air may pass rearwardly of the burner tube and forwardly thereof in the space between said tube and the guard plate 32, as shown by the arrows in Figure 5. This secondary air enters the open bottoms of the radiants R approximately at or just above the flame level of the burners, in order that effective combustion may take place within the radiants. The radiants R act in the manner well known in the art, directing heat and light forwardly, and this heat passes through the transparent wall 78 of the

glass chimney, the light from the radiants being clearly visible through the walls of the said chimney. The burning gases pass upwardly through the radiants and may be discharged through the hood chamber 64 being led therefrom in any appropriate manner.

As further shown by arrows at 88 in Figure 5, fresh air is drawn upwardly from the floor into the vertical flue formed by the chimney 78 through the enlarged opening 74 in the base. As the base is open at its ends as well as in front, this suction of air may be in considerable volume. As the air passes upwardly through the chimney, it is exposed to the action of the radiants R which heat the air and accentuate the convection effect, the pure heated air being discharged from the top of the chimney as shown by the arrows in Figure 5, to provide upwardly directed fresh air convection heat for the room.

While various arrangements may be provided to assemble the parts as just described together, it will be understood that the arrangements shown are quite desirable from the standpoint of cheapness of manufacture. The arrangement wherein the forward and rear sections of the base are secured together and to the burner guard plate 32 is quite important, for when these parts are thus connected, a rigid foundation is then provided for the remaining elements of the heater. As shown, the vertical finishing strip 40 is fitted over the bolts 25, and the upper end of this strip has a suitable aperture to receive the threaded end of a tie rod 70 which extends entirely through the top of the heater, being retained by nuts 71 on the ends of the tie rod. By this arrangement, the hood of the heater is properly held on the back, the latter being in turn supported on the base as described.

The burner tube 30 may be mounted in any suitable way in the base, but I have shown it bolted at its ends as at 51 to wells 49 which depend from the radiant supporting plate 48.

While the forward section of the base may be supported by integral legs 16, the decorative appearance of the heater may be enhanced by providing andiron legs 90 at the front thereof, as shown in Figures 1, 2 and 3. These andirons may be of various designs, and can be removably connected on leg brackets 92 which curve outwardly and forwardly from the front of the heater as shown in Figure 3. Referring to Figure 3a, each leg bracket has an upwardly bent arch shaped cross section as shown at 94, and through the top plate of this arch a bolt 96 is passed, the head of said bolt being counter-sunk in the flange 76 of the base which supports the glass chimney. A corner combing 98 on the forward part of the base acts as a skirt to hide this connection, and the lower edge of the combing may be received in a shallow channel 99 at the rear of the horizontal portion 92 of the leg and adjacent the edge of the arch 94.

A modification of the back and hood is shown in Figures 8 through 13. The upper edge of the back B' is somewhat modified to accommodate the hood, the latter being cast or otherwise formed of metal, and having a front lip which depends downwardly in front of the top of the radiants of a novel corrugated radiator design, in order to exact the maximum of useful heat from the burned gases before they are permitted to discharge through a pipe 102 in the rear wall of the hood. The top wall 104 of the hood is spaced from the top of the back throughout the length of the heater to provide a gas space 106, and

this top surface 104, being of somewhat extensive area, provides for substantial heat transfer by upward radiation into the room. The front lip of the hood is provided with a number of outwardly extending jackets 108, and as shown in Figure 10, these jackets provide spaced substantially separate pockets 110 for the burned gases to pass forwardly into the hood after being deflected by the baffle 112 at the top of the back B'. These gases are permitted to pass forwardly until they strike the front part of the top 104 being then caused to abruptly change direction through almost 180° and then move along the inner face of the top wall 104. These changes in direction of the gases cause a considerable radiation of heat upwardly, forwardly and downwardly. Each chamber 110 has a forward radiating wall 114 (see Figure 11), a top radiating wall 115 and side walls 116 and 118, whereby the radiation of heat from said chamber will be maximum.

It will be noted in Figure 8, that the forward radiating wall of the hood extends some distance outwardly over the convection path formed through the chimney 78 and said radiator wall 114 has the effect of deflecting the rising air through the chimney outwardly as it passes upwardly. In addition, the radiator imparts further heat to this air as it passes the surfaces described thereby contributing to the warmth of the room as well as to the acceleration of the convection movement of this air. It will also be observed that the lower edge of the radiator front depends downwardly to such a point as at 119 to confine the upper edges of the radiants, and thus to confine the flow of gas upwardly into the hood. Various structural details of the embodiment of Figures 8 through 12 are not specifically described, it being apparent that they are substantially identical or similar to the embodiments of Figures 1 through 7, as illustrated in the drawings and previously described.

In Figures 14 through 17, I have disclosed another arrangement wherein provision is made to further insure the sealing off of the radiants from the convection air space within the chimney 78. The top of the back section B' altered to receive thereon a modified hood 132, said hood having a front wall 133 with depressions 134 therein to provide additional radiation surfaces 136 and 138 (Figure 16). The forward wall of the hood is spaced a considerable distance outwardly from the radiants, and the lower edge of this forward wall is of wave-like form in order to fit against the upper end of a wavy transparent shield 140 of heat resisting glass or the like which may be formed in one piece, but which is more conveniently made in a plurality of angular cross sectional pieces 141 of transparent heat proof glass or the like carried on a suitable flange on the upper edge of a modified burner guard plate 144. This guard plate may be formed integral with the rear section 145 of the burner, but I have shown the guard plate and the horizontal plate supporting the glass angle members, radiants and back made in one piece and resting on and attached to the back frame member 145 as illustrated in Figures 14 and 15.

As shown in Figure 17, adjacent edges of the angular transparent plates 141 may fit against asbestos rope sealing strips 146 contained in spaced vertical angle plates 148 resting on the horizontal supporting portion of the guard plate 144, as indicated in Figure 17. The angle members 141 are outwardly supported at their upper ends by the wave-like edge of the hood, and the

interior of the hood may carry a cross brace 151 to provide an interior support for the upper ends of the angle members 148. Such a cross brace may be omitted if the vertical angle members 148 are secured with sufficient rigidity to the supporting plate on which they rest, and the brace is therefore not indicated in Figures 16 and 17.

It will be noted that the top edge of the back B' has spaced recesses 152 therethrough which are in alignment with the vertical angle members 148 and with the depressions in the front of the hood. These recesses will permit some direct passage of burned gases from the top of the radiants to the outlet 102.

With the above described embodiment, it will be apparent that not only is a hood provided to receive the burned gases and discharge the same after extracting the maximum amount of heat therefrom, but also means are provided to confine the burning gases at each radiant and insure no mixture of the air passing through the chimney 76 as previously described. The transparent angle members 141 do not materially reduce the bright appearance of the heater, as the radiants are clearly visible therethrough. The wavy shape of the transparent elements 141 causes direct radiation of a great volume of heat from the radiants to the air passing upwardly through the chimney, to add heat thereto. As shown in Figure 14, the hood 132 has a baffling effect on this rising air to cause the same to flow forwardly as well as upwardly when it leaves the chimney.

In this arrangement, there are substantially three channels of flow for gases or air. There is the direct movement of consumed gas upwardly through the radiants, and out through the hood. There is a further movement of hot air upwardly in the spaces 150 in the angle formed by the glass members 141, and this hot air joins the burned gases from the radiants in the radiator hood. There is also the separate movement of air upwardly through the chimney, which is uncontaminated by the burning gases within the remaining parts of the heater.

I claim:

1. A gas heater having a base, a refractory back with a row of radiants forwardly thereof supported on said base, a burner with gas jets carried in said base beneath said radiants, the upper termination of said back comprising a hood having means to receive the burned gases from said radiants and to discharge same, said base having an extension positioned a substantial distance forwardly of said radiants providing an enlarged vertical opening through the base across the front of the heater, a glass chimney positioned on the forward extension of said base and having side walls which reach rearwardly to the front face of the heater at the ends of the row of radiants, said chimney being open at its lower end and having an open upper end to permit an upward convection flow of air therethrough, and a transparent sealing plate mounted on said base and positioned immediately in front of said radiants, the upper end of said plate being formed to substantially enter said hood to confine the passage of burned gases into and through said hood, whereby upward convection flow of heated air separate from the burned gases from said radiants is provided through said chimney and passing in front of said radiants to derive heat therefrom.

2. A construction in accordance with claim 1 wherein one or more of the radiants are covered by separate removable transparent sealing plates,

there being a plurality of said sealing plates which together form a sealing barrier across the front of the radiants to separate the upward flow respectively of burning gases and convection air.

5 3. A construction in accordance with claim 1 wherein each radiant is covered forwardly by a separate transparent removable plate of glass or the like, and which is of angular horizontal cross section in order to form a passage for heated 10 gases and air in front of said radiants.

4. In a gas radiator, a base comprising separate metal front and rear sections having respective integral front and rear legs, and having respective vertical connecting flanges at each 15 end of the base, said flanges having inner faces presented toward one another and outer faces, a radiant carrying plate supported adjacent the top edge of said base, a gas burner supported in said base below said plate, a guard plate for 20 said burner positioned forwardly of same, said guard plate having rearwardly directed end portions extending to points immediately within the engaging flanges of said base members, respective tie bolts extending through the end portions 25 of said guard plate and between said respective flanges of said base member, and clamps on the outer ends of said bolts engaging the outside faces of said flanges of said base members to lock them together and in proper relation to said guard 30 plate, whereby to provide a rigid mounting for the radiant carrying plate and radiants.

5. A construction in accordance with claim 4 wherein the heater includes a back supported on said base and a hood on said back, and wherein 35 vertical supporting members are provided at the ends of the base and extending upwardly to retain said back and hood in proper position on said base.

6. A gas heater comprising a hollow enclosing 40 casing open at its top and bottom, said casing comprising vertically disposed front and rear walls and opposite end walls and having spaced supporting legs depending therefrom providing a bottom air inlet, a series of elongated hollow 45 vertical radiants supported on said casing adjacent its rear wall, a burner supported on said casing between its end walls, said burner having gas jets positioned beneath said radiants, the 50 front wall of said casing comprising a flat transparent panel of heat resistant glass in horizontal alignment with and of height substantially equal to the height of said radiants, said panel being spaced a substantial distance forwardly of said radiants and forming with said end walls an unimpeded vertical air flue forwardly of said radiants which is open at its bottom to said bottom air inlet and which opens to the atmosphere directly above said front transparent panel, whereby to provide for free upward convection flow of 55 a current of fresh air through said flue, said transparent panel providing for the visibility of said radiants from the front of the heater and the direct forward radiation of heat and light therefrom across said flue and through said front wall.

7. A construction in accordance with claim 6 wherein said radiants are provided with a hood constructed to direct the burning gases which rise therethrough rearwardly away from the current of fresh air which discharges from said flue.

8. A gas heater having a base member, a refractory back with a series of radiants forwardly thereof supported on said base member, said base member having a portion extending a sub-

stantial distance in front of said radiants and having an enlarged vertical opening therethrough across the front of the heater, and a chimney supported on the forward extension of said base member, said chimney having end walls and a flat impervious front wall of transparent heat resistant glass but being open at its rearward side toward said radiants and being open at its lower end to permit entry of air, the front wall of said chimney terminating at a height substantially level with the tops of said radiants providing an opening for discharge of air to the atmosphere, whereby to provide an upward convection flow of heated air through said chimney and passing in front of said radiants, said

convection flow of heated air augmenting the direct forward radiation of said radiants.
